(57) **CLAIM**

The ornamental design for an automobile tire, as shown and described.

DESCRIPTION

FIG. 1 is a perspective view of an automobile tire, it being understood that the tread pattern repeats uniformly throughout the circumference of the tire.

FIG. 2 is a front elevation view thereof.

FIG. 3 is a rear elevation view thereof.

FIG. 4 is a right side elevation view thereof.

FIG. 5 is a left side view thereof.

FIG. 6 is an enlarged fragmentary front elevation view thereof; and,

FIG. 7 is a cross-sectional view thereof taken along line 7—7 in FIG. 6.
